JUSTUS H. HENKES, OF VINCENNES, INDIANA.

FRIENDSHIP-CHAIN.

1,246,598.

Specification of Letters Patent. Patented Nov. 13, 1917.

Application filed April 13, 1917. Serial No. 161,870.

To all whom it may concern:

Be it known that I, JUSTUS H. HENKES, a citizen of the United States, residing at Vincennes, in the county of Knox and State 5 of Indiana, have invented a new and useful Friendship-Chain, of which the following is a specification, reference being had to the accompanying drawings and to the letters and figures of reference marked thereon.

10 This invention relates to the type of chain that is composed of links which are connected together, one or more at a time, the invention having reference more particularly to chains of which the several links 15 are contributed by friends of the possessor of the chain, so that such chain may be first used as a bracelet and subsequently when the chain is increased in length as a neck chain whereby to carry a fan or a 20 muff.

An object of the invention is to provide an improved link of the above-mentioned character and means for connecting links together so that they cannot become accidentally separated nor be readily disconnected intentionally one from another. Another object is to provide a chain of the above-mentioned character that shall be so constructed as to permit the various links of 25 the chain, while being worn, to turn or rotate relatively to the others, so that portions of the chain may roll on the wearer's garment or be handled freely without the links being liable to become tangled due to knotting or kinking of the connecting devices 30 of the links; a further object being to provide improved connecting devices of such construction that will permit the unskilled to readily connect them together and so as 35 to be permanently locked to the friendship links, which devices shall be inexpensive and reliable and durable and economical in 40 use.

With the above-mentioned and other objects in view, the invention consists in an improved chain link provided with connecting rings or eyes adapted to be permanently locked to the link, for permanently connecting the links of a chain together 45 and permitting relative turning or rotation of the links; the invention consisting also further in the novel construction and in

the parts and combinations of parts as hereinabove particularly described and further defined in the accompanying claims. 55

Referring to the drawings,—Figure 1 is a side view of a chain constructed substantially in accordance with the invention; Fig. 2 is a longitudinal central section of two of the improved links connected together; Fig. 3 is a fragmentary longitudinal section of one of the improved links with which is illustrated two of the improved connecting devices, one of the devices being shown as when being connected 60 to the other; Fig. 4 is a fragmentary central section of the link showing two of the connecting devices of which one is in readiness to be connected to another link; Fig. 5 is an end view of one of the improved 65 links of the many-sided design; Fig. 6 is a fragmentary central section of two of the improved links and two of the connecting devices of which one is connected to one of the links and the other in position as when 70 being connected to the other of the links; Fig. 7 is an end view of one of the improved links of cylindrical form; Fig. 8 is an end view 75 of one of the links of triangular contour in cross section; Fig. 9 is an end view 80 of one of the improved links having four sides or faces; Fig. 10 is a transverse section of one of the many-sided links having one of the connecting devices locked thereto; Fig. 11 is a perspective view of one of 85 the connecting devices on an enlarged scale; and, Fig. 12 is a longitudinal central section of one of the improved links having slightly modified ends.

Similar reference characters on the different figures of the drawings indicate corresponding elements, parts or features of construction hereinafter particularly referred to.

The improved chain comprises a number 95 of links having bodies or main portions 1, 2, 3, 4, 5, 6, 7, 8 that are connected one to another, each body being hollow or tubular and having an end portion or head on each end thereof. The body portions of the links 100 may be variously formed as illustrated, some being hexagonal or many-sided, others having a lesser number of external side faces or panels to receive suitable engrav-

ing. One body portion 6 has a flat end or head 9 set in and secured in one end thereof and a similar end or head 10 secured in the opposite end thereof, one end or head having a central aperture 11, the other having a central aperture 12 therein to receive the shank of a connecting ring or eye. An adjacent link body portion 7 has ends or heads 13 and 14 secured therein that also have central apertures 15 and 16 respectively. In some cases cylindrical body or main portions 17 are provided having circular ends or heads 18 in each of which is an aperture 19; in other cases three-sided or triangular body portions 20 being provided that have ends or heads 21 which are triangular in plan and have each an aperture 22 therein.

One end of each link is provided with a connecting ring or eye 23, the opposite end being provided with a similar ring or eye 23' each ring or eye having a shank that is inserted in the aperture in an end or head of a link so as to rotate in the aperture and is permanently locked therein. The terminal ring or eye of one terminal link has a ring 24 connected thereto which may be readily connected to the terminal ring or eye of the remaining terminal link to form a continuous chain. Each ring or eye is non-continuous and has two shank members 25 and 26 that extend from opposite sides of the gap in the ring or eye in spaced apart relation so as to permit the ring or eye of another connecting device to pass between the members in order to connect the rings together. Each shank member is half round, the inner side opposite to the other member being flat, the outer side being curved convexly, so that when the two members are pressed together they jointly are approximately cylindrical, the ring or eye being composed of wire which is elastic. The shank members have flat projections 27 and 28 thereon to the ends of which wings 29 and 30 are connected respectively, the projections and the wings being relatively thin and elastic, the wings normally extending along the outer sides of the projections and flaring away from them. The companion ring or eye has similar shank portions 25' and 26' on which are projections 27' and 28' having wings 29' and 30' thereon respectively for connection with a companion link. One ring is readily connected to another by simply forcing with slight pressure the body of one ring between the projections and thence between the shank members of the companion ring. When the shanks are moved into the apertures in the ends of the heads of the links, the ends of the wings which are blunt are opposed to the inside of the ends of the heads adjacent to the aperture, and are not accessible, so that the

shanks cannot by hand be released from the link.

In some cases the links 17' may have integral ends or heads 31 and 32 in which are apertures 33 and 34 respectively to receive the shanks of the connecting rings or eyes, such modification being shown in Fig. 12.

In practical use the chain when composed of very few links may be used as commonly by connecting a ribbon or tape to the ends of the chain until by repeated additions of links the chain becomes sufficiently long to be used first as a bracelet and subsequently as a neck chain, as will be understood. In case the links happen to be rotated or turned relatively to others, relative rotary movements of the shanks of the rings or eyes is permitted and therefore the chain does not become kinked and liable to be broken in an attempt to straighten it.

Having thus described the invention, what is claimed as new is—

1. A friendship chain link comprising a hollow body with an aperture in each of its opposite ends, and a pair of non-continuous elastic rings, each ring having two shank members that are inserted into one of the apertures and said shank members being provided each with an elastic wing sprung away from the shank member to engagement with the inside of the end of the link. 95

2. A friendship chain link comprising a hollow body and two end portions with an aperture in each end portion, and two non-continuous rings, each ring having two shank members that elastically stand apart to permit another ring to pass between them, each of the shank members having a flat projection thereon and a flat elastic wing on the end of the projection and extending back toward the ring and outwardly, the shank members and the wings being inserted into one of said apertures and the ends of the wings engaging the inside of the end portion of the hollow body to non-removably retain the shank members in the aperture. 100 105 110

3. A chain comprising links, each link consisting of a hollow body portion and two end portions with a central aperture in each end portion, and a ring for each end portion, each ring having a shank that is insertible into one of the apertures to rotate therein, the shank having wings thereon that are elastic to spring away from the shank to the inside of the end portion of the link, each wing having a terminal end to inaccessible engage the end portion and permanently connect the ring to the link. 115 120 125

4. In a friendship chain, the combination with a plurality of links, each link being hollow with an aperture in each of its opposite ends, of a pair of non-continuous elastic rings connected together, each ring having

two shank members that are half-round and elastically stand apart to permit another ring to pass between them, each of said members having a flat projection thereon and an elastic wing on the projection having a blunt end, said shank members being inserted in one of the said apertures to rotate therein, said blunt ends being adapted to engage the end of the link and non-remov-

ably retain said shank members in said aperture. 10

In testimony whereof, I affix my signature in presence of two witnesses.

JUSTUS H. HENKES.
